FIG 5

Inventor

Alfred H. Emery.

By his Attorney

John Thompson

UNITED STATES PATENT OFFICE.

ALFRED H. EMERY, OF POUGHKEEPSIE, NEW YORK.

MILK-BOTTLE-CAP REMOVER.

Application filed January 20, 1928. Serial No. 248,212.

This invention relates to a tool or device for removing the card board caps from milk bottles or the like, and if so desired after the cap is removed from the bottle, it may 5 be retained by the remover and by it again used to close the bottle until such time as the bottle has been emptied.

While there are devices now employed for this purpose, they have many disadvantages, 10 among which are the fact that no proper grip is afforded for the fingers of the operator, nor do they afford or comprise an air tight cap in the event that it is desired to reinsert the cap into the bottle, as they 15 are constructed with openings in the bottom thereof communicating with the holes made in the bottle cap by the engaging prongs.

The object of the invention is to produce a device of this kind, stamped or otherwise 20 produced from a single piece of metal or other suitable material, and which shall be cheap to manufacture, durable and sanitary, and which may be imprinted with advertising matter for free distribution by milk 25 dealers and others.

Another object of the invention is to provide a device of this kind, that shall when attached to the bottle cap produce an air 30 tight stopper for the bottle.

With these and other objects in view, my 35 invention consists in certain construction and combination of parts as will hereinafter be fully described and claimed, and fully illustrated in the accompanying drawing 40 which forms a part hereof and in which like figures of reference refer to corresponding parts in all of the views, but it is to be understood that slight changes may be made therein without departing from the spirit 45 of the invention.

In the drawings:—

Figure 1 shows the upper or neck portion 50 of a milk bottle in section, with the remover applied to the cap, and in position for removing the same.

Figure 2 shows a top plan view of the cap remover.

Figure 3 shows a bottom view of the blank before the same is formed, but after the 55 prongs have been punched.

Figure 4 shows a side or edge view of the cap remover.

Figure 5 shows a bottom view of the same

after the blank shown in Figure 3 has been formed into the finished shape. 55

Referring to the drawings:—

The usual milk bottle neck is indicated by the numeral 10; the same being provided with the flange or groove 11, within which is held the regular card board cap or disk 13. 60

The cap remover comprises a piece of sheet metal or other suitable material, which is blanked or cut from the sheet and of the shape as shown in Figure 3, and which is adapted to be formed or folded on the dotted 65 lines A—A, B—B, and C—C.

From this blank the two prongs or cork screw points 14 are sheared or struck up from the blank, and in the positions as shown, and formed from that portion of the blank located between the dotted lines 70 A—B, and C—D, and which when formed correspond to the web 16, each opening from which a prong 14 is sheared being covered by the other part of said web 16, and the 75 prongs 16 projecting as shown in Figures 4 and 5, from that part of the blank forming the bottom 12; said prongs being positioned at diametrically opposite points and being oppositely curved or inclined, for the purpose 80 of entering and engaging the cap 13, when the remover is placed thereon and given a rotary movement by the hand of the operator or user; the cap being removed or inserted by such a rotary or screw movement. 85

For providing a finger grip for the operator or user, the blank is formed with a tubular portion 15 formed from that portion of the blank between the dotted lines B—C and joining the two sides of the web 16. 90

It will thus be seen that the bottom of the cap remover presents a round flat surface 12 of slightly smaller diameter than that of the cap 13, so that it is readily centered or located in the top of the bottle neck; and from this flat surface, two sharp prongs project at an angle and pointed in opposite directions; while the upper part of the cap remover is provided with a finger hold, by which it may be gripped, pressed upon the bottle cap and rotated slightly to insert the prongs into the cap, when by an upward pull the cap is removed from the bottle, or again inserted by a slight downward pressure. 95

Should the caps be very tight in the bottles, the tubular finger hold 15, may be used 100

to provide leverage by inserting therein a rod, or tine of a fork, etc.

Having thus described my invention, what I claim as new and desire to secure by Letters Patent, is:

A device of the class described, comprising a flat circular portion composed of two solid portions semicircular and formed from

the same piece, a web formed from the same piece at right angles thereto and adjacent 10 to the abutting edges of said semicircular portions, prongs struck from said web and projecting at an angle with and below said circular portion.

In testimony whereof I affix my signature.

ALFRED H. EMERY.
